US00D737497S

(12) **United States Design Patent**
Burgess et al.

(10) **Patent No.:** US D737,497 S
(45) **Date of Patent:** ** Aug. 25, 2015

(54) **QUICK CHANGE LENS GASKET**

(71) Applicants: **Paul Burgess**, Lodi, NJ (US); **Stephanie Burgess**, Lodi, NJ (US)

(72) Inventors: **Paul Burgess**, Lodi, NJ (US); **Stephanie Burgess**, Lodi, NJ (US)

(**) Term: **14 Years**

(21) Appl. No.: **29/482,914**

(22) Filed: **Feb. 24, 2014**

(51) **LOC (10) Cl.** 26-99

(52) **U.S. Cl.**

USPC **D26/113**

(58) **Field of Classification Search**

(57) **CLAIM**

The ornamental design for a quick change lens gasket, as shown and described.

DESCRIPTION

FIG. 1 is a perspective view of the top of the quick change lens gasket in full lines.

FIG. 2 is a perspective view of the bottom of the quick change lens gasket in full lines.

FIG. 3 is a top plan view of the quick change lens gasket.

FIG. 4 is a bottom plan view thereof.

FIG. 5 is a right side elevation view thereof.

FIG. 6 is a left side elevation view thereof.

FIG. 7 is a front elevation view thereof.

FIG. 8 is a rear elevation view thereof; and,

FIG. 9 is a perspective view of the quick change lens gasket in full lines shown in use on a sandblaster in broken lines representing environmental association matter being for illustrative purposes only and forming no part of the claimed invention.

1 Claim, 5 Drawing Sheets
